DIES FOR ROTARY THREAD ROLL DIE MACHINES FOR PRODUCING SCREWS

Frederick William Cooper, Birmingham, England, assignor to GKN Screws and Fasteners Limited, Birmingham, England, a British company

Filed Jan. 16, 1963, Ser. No. 251,830

4 Claims. (Cl. 72—104)

In my prior application No. 144,123, filed October 10, 1961, there is described and claimed an invention relating to dies for a rotary die thread rolling machine of the generally known type having a rotary die provided with a thread form around its circumference and co-operating with a stationary die which is of segmental form and extends around part of the circumference of the rotary die and wherein a number of blanks are introduced one after another into the space between the rotary die and stationary die so that each blank is rolled through to the exit end of the stationary die and the thread is impressed upon the blank.

Such prior application together with the present invention are concerned with the production of screws and the like having a particular form of thread and which screws are described as being "spaced thread type." This is a type of screw having a thread form which cannot be produced by thread rolling using a conventional die having a constant cross-section from one end to the other or around its circumference due to the fact that the convolutions of the thread are spaced apart by a substantial distance. Self-tapping screws which have a substantial length of flat core between adjacent thread convolutions are a good example of this type of screw which I describe as "spaced thread type" and where the grooves between adjacent threads are not of a sharp character. Screw nails, drive screws, drive nails, and the like also come in this category and are included within the term "screws" as used herein.

In this type of screw the corresponding form of the die as previously used has a rib of flat top, rounded, or other "non-sharp" section at the finishing end to produce the groove between the threads and, as produced on machines having flat dies hitherto, it has been necessary to have a die of changing cross-sectional form from end-to-end such that at the starting end of the die the form of the rib is of a sharp V-section to produce the desired initial deforming of the metal with relatively small pressure and this form changes progressively along the length of the die to the final required flat top or other non-sharp form of the ribs at the finishing end of the die.

There is another method of rolling threads on screws which has certain advantages in economic and rapid production and this involves the use of two or three co-operating rolls each having a thread form around its circumference and the blank being fed into the nip between co-operating rolls. Hitherto it has not been feasible to produce spaced thread type screws by this method of rolling and the object of the invention is to provide improvements which will enable this to be done.

According to the invention there is provided means for producing spaced thread type screws by rolling between co-operating die rolls wherein one roll has a thread form which is of constant cross-section being somewhat similar to that which is required to produce the spaced grooves and thread of the screw but with the crest of each rib on the die roll being interrupted to give the ribs a degree of sharpness sufficient to ensure that the material of the blank is initially deformed with comparatively light pressure.

The invention is illustrated in the accompanying drawings wherein:

2

FIGURE 1 is a perspective diagrammatic view of the rolls in a thread rolling machine.

FIGURE 2 shows two fragmentary views of sections on the lines A—A and B—B in FIGURE 1.

5 FIGURE 3 is a perspective diagrammatic view of two rolls in a thread rolling machine having a modification of the invention.

FIGURE 4 shows fragmentary views of sections on the lines A—A, B—B in FIGURE 3.

10 The drawings show only the actual thread forming rolls which operate upon the blanks to produce screws in well-known manner. The machine which incorporates such rolls is of well-known form and is not shown as the construction and operation of such machines is well-known to those engaged in this art and further reference thereto is unnecessary.

The examples shown in FIGURES 1 and 2 of the accompanying drawings illustrate two driven rolls mounted about spaced parallel axes and there are generally known two types of such machine. In one type, the rolls are of the same diameter and are driven at the same speed and are arranged in the machine so that the axes of rotation of the rolls can be displaced so as to move the rolls apart and move the rolls back together and in this type of machine with the rolls moved apart, the blank is placed in between the rolls which are then moved together to engage the blank for the rolling of the thread. In the other type of machine, the rolls rotate about fixed axes and have different diameters or are driven at different speeds or have a combination of these factors and in this type of machine the blank is fed into the nip between the rolls and progresses through the nip to the other side thereof as the thread is being rolled thereon. The invention is capable of application to both these type of machines employing two co-operating die rolls.

20 In the example of FIGURES 1 and 2, the one roll 10 has a constant cross-sectional form of die throughout its circumference as shown by section A—A in FIGURE 2 and in cross-section this die has V-section grooves 13 corresponding to the actual thread to be produced and such grooves 13 being spaced apart by ribs 14 each of which has its crest interrupted to give it a degree of sharpness which it would not have if the crest were flat. As shown, such interruption may take the form of a further 25 shallow groove 15 running along the crest of the rib 14 or there may be two or more such shallow grooves. Such grooves 15 are shallow as compared with the depth of the V-shaped groove 13 which defines the actual thread.

30 In this form of the invention, the other die roll 11 has a constant cross-sectional die form around its circumference the cross-section (see Section B—B) which corresponds exactly with the desired finished thread form on the blank and thus it is constituted by V-section grooves 45 17 spaced apart by flat top ribs 18.

35 The degree of sharpness given to the ribs 14 on the one die 10 will be sufficient to produce the initial deforming of the metal with relatively small pressure when the blank is first contacted by the rolls and as rolling progresses 40 the flat top form of the ribs 18 on the other die 11 will gradually dominate in the gathering and moving of the metal of the blank to produce the final thread form having flat bottom grooves spacing apart the actual thread convolutions.

45 50 The above described form of the invention may be used where the pitch of the screw is not very coarse, that is to say, where the spacing between the grooves of the thread is not very great as compared with the root thickness of the thread convolutions. In this case it is found that the degree of sharpness given to the ribs 14 on the one die is sufficient to ensure the desired initial deforming 55 of the metal.

In a case where the screw has a very coarse pitch then it is preferred to use the form of the invention illustrated in FIGURES 3 and 4 wherein the die roll 11 in the machine of FIGURE 1 is replaced with a roll having a special form of die with certain relieved portions. In this case the die roll 20 is formed in the same way as described in the first example with the crests of the ribs 24 being given the required degree of sharpness by shallow grooves 25 and with the cross-sectional form A—A constant throughout the circumference of the roll 20. In this case however, the second die roll 21 would have its circumference made up from a number of similar segments 30 secured to the roll.

Each such die segment 30 has a cross-sectional form which changes gradually from its starting end, which is the end which first engages the blank, to its finishing end, which is the end of the segment which last makes engagement with the blank as it leaves the nip between the rolls. At the starting end (see Section A—A) the cross-sectional form is the same as, or similar to, the form of the die on the other roll 20, and it consists of a number of V-shaped grooves 23 spaced apart by ribs 24 each rib having its crest interrupted by one or more relatively shallow grooves 25. Instead of this cross-sectional form being constant throughout the length of each segment 30 however, it changes gradually and the shallow groove or grooves 25 in the crests of the ribs 24 gradually lessen in depth until they disappear completely at about two-thirds of the way along the arcuate length of the segmental die (from its starting end) so that over the finishing section (see Section B—B) the cross-sectional form of the die segment provides V-shaped grooves 27 separated by flat top ribs 28.

With this form of the invention, blanks would be indexed by known indexing mechanism into the nip 22 between the rolls 20 and 21 so that a blank was correctly positioned at the starting end of a die segment 30 as this came round in the course of its rotation and in this case the degree of sharpness (from shallow grooves 25) on the ribs 24 of the constant form die roll 20 together with the sharpness provided by the relieved starting section A—A of the segments 30 of the other die roll 21 ensures the initial deforming of the material under relatively light pressure as with the case above described.

In another example the invention may be applied to a further type of this machine having three die rolls arranged with axes passing through the apices of a triangle and the blank being rolled in the gap which is defined between the three rolls. In this case two of the rolls may have the constant cross-sectional die form around their circumference such form being as above described for the rolls 10 and 20, and the third roll would have a constant cross-sectional die form corresponding to the desired thread form and having flat top ribs without any interruption as for roll 11 in FIGURE 1. Such machine may be used for producing a spaced type of thread on a relatively long blank which can be fed through the gap between the rolls in the axial direction to progressively produce the thread along the blank from end-to-end.

What I claim then is:

1. Means for rolling a thread upon a spaced thread type screw in which adjacent convolutions of the thread rib are spaced apart by a flat bottomed groove as herein defined, said means comprising; a pair of co-operating die-rolls each having a thread form comprising grooves, separated by ribs, extending round its periphery at an angle to the axis of the roll corresponding to the helix angle of the thread of the screw, one of said die rolls having a thread form wherein each groove has a cross-section corresponding to the desired cross-section of the thread rib on the screw, and each rib has a cross-section substantially of the form to produce the flat bottomed groove on the screw, but each such rib having its crest interrupted by at least one further groove which extends longitudinally of the rib throughout its length and is of

shallow depth as compared with the depth of each groove for producing the thread rib on the screw.

2. Means for rolling a thread upon a spaced thread type screw in which adjacent convolutions of the thread rib are spaced apart by a flat bottomed groove as herein defined, said means comprising; a pair of co-operating die-rolls each having a thread form comprising grooves, separated by ribs, extending round its periphery at an angle to the axis of the roll corresponding to the helix angle of the thread of the screw, one of said die rolls having a thread form wherein each groove has a V cross-section corresponding to the desired cross-section of the thread rib on the screw, and each rib has a cross-section substantially of the form to produce the flat bottomed groove on the screw, but each such rib having its crest interrupted by at least one further groove of V cross-section which extends longitudinally of the rib throughout its length and is of shallow depth as compared with the depth of each groove for producing the thread rib on the screw; the other of said die rolls having a thread form wherein each groove has a V cross-section corresponding to the desired cross-section of the thread rib on the screw, and each rib has a flat crest to produce the flat bottom groove on the screw.

3. Means for rolling a thread upon a spaced thread type screw in which adjacent convolutions of the thread rib are spaced apart by a flat bottomed groove as herein defined, said means comprising; a pair of co-operating die-rolls each having a thread form comprising grooves, separated by ribs, extending round its periphery at an angle to the axis of the roll corresponding to the helix angle of the thread of the screw, one of said die rolls having a thread form wherein each groove has a cross-section corresponding to the desired cross-section of the thread rib on the screw, and each rib has a cross-section substantially of the form to produce the flat bottomed groove on the screw, but each such rib having its crest interrupted by at least one further groove which extends longitudinally of the rib throughout its length and is of shallow depth as compared with the depth of each groove for producing the thread rib on the screw, the other of said die rolls having its circumference divided into a number of similar die segments, each segment comprising grooves corresponding to the desired cross-section of the thread rib on the screw, and ribs, each of which has a cross-section which changes gradually from its starting-end to its finishing end, the cross-section at the starting-end of each rib being substantially of the form to produce the flat bottomed groove on the screw, but each such rib having its crest interrupted by at least one further groove which is of shallow depth as compared with the depth of each groove for producing the thread rib on the screw, such shallow depth groove decreasing in depth to zero as it extends longitudinally of the rib and the cross-section at the finishing end of each such rib being of flat crest form to produce the flat bottom groove on the screw.

4. Means for rolling a thread upon a spaced thread type screw in which adjacent convolutions of the thread rib are spaced apart by a flat bottomed groove as herein defined, said means comprising; a pair of co-operating die-rolls each having a thread form comprising grooves, separated by ribs, extending round its periphery at an angle to the axis of the roll corresponding to the helix angle of the thread of the screw, one of said die rolls having a thread form wherein each groove has a V cross-section corresponding to the desired cross-section of the thread rib on the screw, and each rib has a cross-section substantially of the form to produce the flat bottomed groove on the screw, but each such rib having its crest interrupted by at least one further groove which extends longitudinally of the rib throughout its length and is of shallow depth as compared with the depth of each groove for producing the thread rib on the screw; the other of said die rolls having its circumference divided

into a number of similar die segments, each segment comprising grooves of V cross-section corresponding to the desired cross-section of the thread rib on the screw, and ribs, each of which has a cross-section which changes gradually from its starting end to its finishing end, the cross-section at the starting end of each rib being substantially of the form to produce the flat bottomed groove on the screw, but each such rib having its crest interrupted by at least one further groove of V cross-section which is of shallow depth as compared with the depth of each groove for producing the thread rib on the screw, such shallow depth groove decreasing in depth to zero as it extends longitudinally of the rib and the cross-section

at the finishing end of each such rib being of flat crest form to produce the flat bottom groove on the screw.
